[57] CLAIM

The ornamental design for an internal combustion engine, as shown and described.

DESCRIPTION

FIG. 1 is a front elevational view of an internal combustion engine showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a right side perspective view thereof;

FIG. 8 is a left side perspective view thereof;

FIG. 9 is a right side perspective view of an alternative embodiment thereof, the only difference residing in the configuration of the support elements at the base; and FIG. 10 is a left side perspective view of the embodiment of FIG. 9.

FIG. 1

FIG. 2

FIG. 3

FIG. 4

FIG. 5

FIG. 6

FIG. 7

FIG. 8

FIG. 9

FIG. 10
